US00D949011S

(12) **United States Design Patent** (10) **Patent No.:** **US D949,011 S**
(45) **Date of Patent:** **** Apr. 19, 2022**

(54) **PACKAGING CONTAINER SHEET**

(71) Applicant: **TOPPAN PRINTING CO., LTD.**,
Tokyo (JP)

(72) Inventor: **Isao Kojime**, Tokyo (JP)

(73) Assignee: **TOPPAN PRINTING CO., LTD.**,
Tokyo (JP)

(**) Term: **15 Years**

(21) Appl. No.: **29/736,814**

(22) Filed: **Jun. 3, 2020**

(30) **Foreign Application Priority Data**

Dec. 5, 2019 (JP) 2019-026994

(51) **LOC (13) Cl.** **09-03**

(52) **U.S. Cl.**

USPC **D9/433**

(57) **CLAIM**

The ornamental design for a packaging container sheet, as shown and described.

DESCRIPTION

FIG. 1 is a front view of a packaging container sheet showing my new design;

FIG. 2 is a rear view thereof;

FIG. 3 is a top plan view thereof;

FIG. 4 is a bottom plan view thereof;

FIG. 5 is a right side view thereof;

FIG. 6 is a left side view thereof;

FIG. 7 is an unfolded front view thereof; and,

FIG. 8 is an unfolded rear view thereof.

The broken lines illustrate portions of the packaging container sheet that form no part of the claimed design. The dash-dotted lines in the drawings depict claimed fold lines.

1 Claim, 6 Drawing Sheets
